FOLDABLE VOTING BOOTH

John W. Babbs, Torrance, Arthur H. Krugler, Whittier,
and Harry D. Jacoby, Palos Verdes Estates, Calif.,
assignors to Hitco

Filed Feb. 20, 1970, Ser. No. 21,548

Term of patent 14 years

Int. Cl. D6—04

U.S. Cl. D33—7

FIG. 5.

FIG. 6.

FIG. 7.

FIG. 8.

FIG. 1 is a perspective view of a foldable voting booth in its fully unfolded condition, showing our new design.

FIG. 2 is a side elevation view thereof.

FIG. 3 is a rear elevation view thereof.

FIG. 4 is a top plan view thereof.

FIG. 5 is another perspective view thereof in a partially folded condition.

FIG. 6 is another perspective view thereof in a further partially folded condition.

FIG. 7 is another perspective view thereof in a still further partially folded condition.

FIG. 8 is another perspective view thereof in a completely folded condition.

We claim:

The ornamental design for a foldable voting booth, substantially as shown.
